[57] CLAIM

The ornamental design for undercabinet lighting fixture, as shown and described.

DESCRIPTION

FIG. 1 is a perspective view of an undercabinet lighting fixture of the present invention;

FIG. 2 is a top plan view of the undercabinet lighting fixture;
FIG. 3 is a bottom plan view of the undercabinet lighting fixture;

FIG. 4 is a front elevational view of the undercabinet lighting fixture;

FIG. 5 is a back elevational view of the undercabinet lighting fixture;

FIG. 6 is a left side elevational view of the undercabinet lighting fixture; and,

FIG. 7 is a right side elevational view of the undercabinet lighting fixture.

The broken lines are shown for illustrative purposes only and form no part of the claimed design.
